JOHN WARNE PHILLIPS, OF BRIDGEPORT, CONNECTICUT

NECKTIE HOLDER

Application filed July 19, 1930. Serial No. 469,010.

This invention relates to new and useful improvements in necktie holders.

An object of the invention is to provide a form or holder for a four-in-hand necktie, the holder being preferably of substantially wish-bone shape and of sheet metal and including means for attaching it to a collar button whereby to secure it in place.

Another object is to provide a necktie holder substantially in the form of a wish-bone and wherein the wing portions of the holder are warped or turned at an angle to the stem or tongue portion whereby the wings will conform to the inner band of the collar and will not press outward against the outer flap or turned down portion of the collar and the upward curved ends of the wings engage the crease of the collar.

A further object is to provide a necktie holder which will be substantially concealed by the folds of the tie without detracting from its appearance and which includes an elastic means to be secured at one end to a collar button and secured at its other end to the turned out lower portion of the holder whereby there is a tendency to rock or fulcrum the holder resulting in its being securely held in the folds of the collar.

Other objects and advantages will become apparent from a consideration of the following detailed description taken in connection with the accompanying drawings showing a satisfactory embodiment of the invention. However, it is to be understood that the drawings and this description are for the purpose of making clear the construction and operation of the invention and that they are not to be considered in a limiting sense as reference must be had to the claims for a definition of the limitations of the invention.

In the drawings:

Fig. 1 is a front elevational view of the holder, a tie being disposed thereon in accordance with the invention and a portion of a collar being indicated in dotted lines to show the application of the invention.

Fig. 2 is a side elevation of the device as shown in Fig. 1.

Fig. 3 is a side elevation of the holder by itself.

Fig. 4 is a side elevational view of the device showing a step in the formation of the knot, the tie being shown by dotted lines, and

Fig. 5 is a front view of the device illustrating a step in the formation of the knot, the tie being shown in dotted lines.

Referring in detail to the drawings at 7 is indicated by dotted lines a portion of a collar including wings 8 and 9 as is usual. The invention comprises the form or holder 66 generally indicated at 10 and which as shown is substantially in the form of a wish-bone.

Holder 10 comprises wings 11 and 12 and a tongue or stem 13. Wings 11 and 12 extend upwardly and rearwardly and are warped or turned at a sharp angle relative to the stem 13 so that the upper end portions of the wings are in planes at an angle to the plane of the stem 13 and will conform to and grip the inner fold of the collar when in place.

The stem 13 is longitudinally curved outwardly and extends downwardly from the wings and at its lower end is curved or turned inwardly to provide an eye 14. Further, stem 13 is transversely curved as shown to make the stem more rigid.

An elastic medium, preferably in the form of a coil spring 15, has one of its ends flexibly or hingedly connected in the eye 14 and has its other end similarly connected to a spring socket 16 adapted when the device is in use to be sprung over the head of a collar button 17.

Owing to the fact that the wings 11 and 12 are turned at a sharp angle relative to the stem portion 13 the wings will lie along the inner band of the collar as at 12 Fig. 2 and the stem curving outwardly there will be a tendency for the holder to fulcrum about the point 18, as a result of the pull exerted by the spring 15. This action will cause the holder and the tie carried thereby to be properly held in place, the spring attachment pulling the outwardly curved end of the stem downward causing the curved ends of the wings to kick up and become firmly located in the crease of the collar as at 26 Fig. 2. It is essential that the connecting medium between the holder and the collar button be elastic so

there will be a constant tension exerted holding the tie in position and from the shape of the holder virtually giving a three point bearing, the two ends of the wings and the 5 end of the stem. The tension and support is such that the tie will adjust itself to the various normal stresses when in use without getting out of position.

Since the stem 13 curves outwardly and is 10 disposed in front of the plane of the wings 11 and 12 it will not dig down into the bosom of a shirt. The stem is arranged centrally with respect to the wings. The tie is tied around it and it extends approximately to 15 the lower end of the knot. For small knots or narrow ties the stem should be shortened proportionally. Also, the point or eye 14 being disposed outwardly and upwardly when the holder is in place on a collar, the point 20 of attachment of the spring is raised assisting the fulcruming action above mentioned.

Generally but one shape of a holder Fig. 3, 10—27 will be necessary since it will be used with the usual range of collar heights. 25 However, for extra high collars the ends of the wings are given a sharper up curve as in Fig. 3, 10—28 to reach up and engage the crease of the collar without changing the position of the tie. For extra low collars or 30 soft collars attached to the shirt, the curve of the wings is flattened as in Fig. 3, 10—29 to preserve normal tension and position of the tie.

Additionally, it is pointed out that the 35 transverse curvature of the stem 13 not only serves to stiffen the stem somewhat but also forms a seat or guide for the spring 15 thereby assisting in holding the spring in place and serving to partially conceal the spring.

40 The tie 18 may be of usual length although it will be obvious that a tie of less than the usual length may be used since it does not, according to the present invention, encircle the inner portion of the collar. When forming knot 19, the inner or narrow end portion 45 20 of the tie is disposed over the front of stem 13 and the tie is then carried around the lower portion of wing 12 and then around the stem 13 over the end portion 20 in front of the 50 stem as in Fig. 4.

Next the tie is looped over the wing 11 (Fig. 5) with the portion 21 encircling the wing and the portion 22 at the forward side of the 55 wing and beneath the portion 23. Now, by drawing downwardly on the portion 23 the tie will be drawn into shape forming knot 19. The stem curving outwardly and upwardly the lower end of the spring attaching the 60 holder to collar button is held up and concealed by the lower folds of the knot. The upper part of the spring which is back of the knot is hidden from view by the collar as shown in Fig. 2, 30. The connection 16 to 65 the head of the button is free to turn there

on in all directions and adjust itself according to the direction of pull of the spring.

Having thus set forth the nature of my invention, what I claim is:

1. A necktie holder including a body generally in the form of a wish-bone and having its wing portions curved sharply upward and curved rearwardly and having its stem portion curving downwardly and outwardly and disposed in a plane substantially at 75 right angles to the plane of the free ends of the wings.

2. A necktie holder comprising a body generally in the form of a wish-bone and including upwardly and rearwardly curved wing portions and a downwardly and outwardly curved stem portion, said wing portions adapted to be received in the fold of a collar, a coil spring connected at one end to the free end of said stem, and means on the other end 85 of said spring adapted to be sprung over the head of a collar button to swivelly connect the spring and button.

3. A necktie holder comprising a body having connected wing portions adapted to be received in the creases of a collar, a stem connected to the body intermediate the wings and extending downwardly therefrom, a yieldable resilient means connected to the stem, and swivel means adapted to be sprung over the 95 head of a collar button for connecting the resilient means to a collar button.

4. A necktie holder comprising a body generally in the form of a wish-bone and including backwardly and upwardly extending 100 wing portions and a stem portion, the free end portions of said wings being substantially flat and turned out of the plane of the stem portion so that they will lie in the crease of a collar against the band with the portion 105 of the body adjacent the junction of the stem and wings resting against the forward portion of the band, an elastic medium for connecting the lower end of the stem to a collar button, and the stem being curved downwardly and outwardly away from the band so that the force of the elastic medium will cause the holder to fulcrum at substantially said connection between the stem and wings to hold 110 the wings in position.

5. A necktie holder comprising a body having upwardly and backwardly extending wing portions adapted to be received in the crease of a collar, said wing portions being connected by a curved intermediate portion 120 adapted to engage the front of the collar band to form with the wings a three point support on the collar, a stem connected to the intermediate connecting portion and curved downwardly and outwardly therefrom, a 125 yieldable resilient means connected to the stem adjacent its free end, and means for connecting the latter means to a collar button.

6. A necktie holder comprising a body gen-

erally in the form of a wish-bone and including upwardly and rearwardly curved wing portions and a downwardly and outwardly curved stem portion, said wing portions adapted to be received in the fold of a collar, a coil spring connected at one end to the free end of said stem, and means on the other end of said spring adapted to detachably engage the head of a collar button to connect the spring and button.

10 7. A necktie holder comprising a body generally in the form of a wish-bone and including upwardly and rearwardly curved wing portions and a downwardly and outwardly curved stem portion, said wing portions adapted to be received in the fold of a collar, a yieldable resilient means connected to the free end portion of the stem, and means adapted to detachably engage the head of a 15 collar button holding said collar for connecting the resilient means to said button.

20 In testimony whereof I affix my signature.
JOHN WARNE PHILLIPS.
